UNITED STATES PATENT OFFICE.

ROBERT P. SCOTT, OF BALTIMORE, MARYLAND.

PENCIL-CLASP.

SPECIFICATION forming part of Letters Patent No. 312,296, dated February 17, 1883.

Application filed March 31, 1883. (No model.)

To all whom it may concern:

Be it known that I, ROBERT P. SCOTT, a citizen of the United States, residing at Baltimore city, Maryland, have invented certain new and useful Improvements in Pencil-Clasps, of which the following is a specification, reference being had to the accompanying drawings, forming part hereof, in which—

Figure 1 is a view in perspective of a pocket 10 and a fragment of a garment, showing my improved pencil-clasp with a pencil in position therein. Fig. 2 is a view in perspective of the pencil-clasp unattached, and Fig. 3 is a sectional view of the same.

Like letters of reference mark the same parts 15 in all the figures.

My invention has for its object to furnish a cheap, simple, and reliable device, whereby a pencil or pen-holder may be held securely 20 when in a pocket or other place of safety or storage, and will at all times be ready for instant use as well as at all times ready for securing again, either in the same or some other desired place.

To these ends my invention consists in a pencil-clasp composed of a spring clasp-tube for receiving, encircling, and holding a pencil, and a spring-arm projecting therefrom at the end in a direction substantially parallel 30 with the line of the tube extended, or the pencil when in the tube, said arm being at its point of juncture with the tube bent slightly outward, thence inward to or near said line, and thence outward, terminating at a point 35 outside of said line, whereby when the pencil is inserted in the clasp and placed in a pocket or other receptacle, the spring-bar will pass on the outside thereof, forming one jaw of a clamp of which the pencil forms the other 40 jaw, the spring-bar being formed integral with the clasp-tube, or being rigidly secured thereto.

Referring to the drawings by letter, A is a tube, composed in this case of sheet metal 45 bent into cylindrical form, the edges meeting at a, but not secured together, whereby the resiliency or elasticity of the metal is availed of to close the tube tightly upon any object passed therein. Joined to this tube, (or, as

shown in this instance, formed as part of the 50 same sheet of metal,) at one end thereof, as at b, is a spring-arm, B, the portion b' being bent outward, the portion b² inward, and the end b³ outward, as fully shown. The middle portion, b³, to or near a line drawn from the 55 tube, as at x in Fig. 3, and the end b³, project outside of and at a slight angle to said line. The line x is the line of the pencil when clasped in the tube, and as a consequence of the manner of construction of the spring-arm 60 B, just heretofore described, the point b² thereof is in contact with the pencil when in the clasp, and a space, b⁴, V-shaped, is formed, by means of which the spring-arm readily passes outside of the pocket, when the pencil is pushed 65 in. Thus the pencil is firmly held in the pocket, the outside of the pocket being clamped between the pencil and the spring-arm. The pencil in this position is shown in Fig. 1, and is marked C.

It will be seen that the pencil cannot drop out of the clasp, nor can the clasp drop off the pocket; but the pencil and clasp may be readily removed together, and the clasp and clamp will in nowise interfere with the use of 75 the pencil. No manipulation of the spring-clamp arm is necessary, its action being self-adjusting.

The whole device always remains on the pencil and the pencil may be clamped and 80 held on the lapel of a coat, a waistband, or a suspender, as well as in position shown.

The tube may be made of coiled wire, the end thereof forming the spring-bar.

The device is extremely simple and cheap 85 and at the same time thoroughly reliable.

What I claim, and desire to secure by Letters Patent of the United States, is—

1. A pencil-clasp consisting of a tube provided with a spring-arm projecting from it 90 and extending beyond its end, whereby when the pencil is in position in the tube it will form one jaw of a clasp of which the projecting end of the spring-arm forms the other jaw, which clasp serves to retain the pencil in 95 position in the pocket, as set forth.

2. The pencil-clasp herein described, consisting of the clasp-tube A, having the arm

B, projecting at b from it and beyond the end thereof, and having an outward-projecting end, b' , as and for the purpose set forth.

3. The spring pencil-clasp, consisting of 5 clasp-tube A, having the spring-arm B formed integral therewith and projecting from and beyond the end thereof, said arm being bent outward at b' and b'' and inward at b^2 , as and for the purpose set forth.

In testimony whereof I affix my signature to in presence of two witnesses.

ROBT. P. SCOTT.
